UNITED STATES PATENT OFFICE

2,556,774

REGULATION OF LIQUID FUEL INJECTION
PUMPSWilfrid Edward Walter Nicolls, Pinner, England,
assignor to C. A. V. Limited, London, EnglandApplication November 7, 1950, Serial No. 194,406
In Great Britain August 21, 1948

2 Claims. (Cl. 103—37)

1

This invention relates to liquid fuel injection pumps for use with internal combustion engines, and of the kind having combined therewith means for automatically varying the pump output in response to different speed conditions. When starting an engine it is usually desirable to supply the fuel in excess of the normal maximum amount, and the object of the present invention is to provide improved means for satisfying this requirement.

The invention comprises the combination with the governing means of the pump, of a spindle angularly operable by an attendant, an arm in fixed relation to the spindle and adapted to co-operate with the governing means, a second arm forming a two-part stop and freely mounted on the spindle, a spring device for interconnecting the stop arm with the spindle, a spring acting on the stop arm, and an abutment movable by the governing means and adapted to co-operate with the stop arm.

In the accompanying drawings:

Figure 1 is a part sectional side elevation illustrating an application of the invention to a known form of centrifugally actuated fuel pump regulating means, and Figure 2 is a similar view to Figure 1, illustrating an application of the invention to a fuel pump regulating means which is actuated pneumatically in response to variations in the air induction manifold of the engine.

Figures 3 and 4 are part sectional side elevations illustrating, in different working conditions, the mechanism forming the subject of the present invention, and

Figure 5 is a sectional plan of the mechanism.

Referring to Figure 1, a well known form of reciprocating fuel injection pump has combined with it a slidable bar *a* for actuating the delivery regulating means of the pump, and in association with the rotary driving spindle of the pump is arranged a centrifugal governor *b*. The latter is connected to the bar *a* by a lever *c* which is also operable by a lever *d* under the control of the attendant. Variations in the speed of the engine result in longitudinal movements of the bar by the governor for varying the quantity of fuel discharged to the engine in each stroke of the pump. An alternative known means for actuating the bar *a* is shown in Figure 2, where the said bar is connected to a diaphragm *e* loaded by a spring *f*. The chamber *g* at one side of the diaphragm is adapted for connection to the air induction manifold of the engine, and variations of pressure in the mani-

fold are accompanied by corresponding movements of the bar *a*.

In applying the present invention to either of the forms of governing means above described, there is provided a spindle *h* which is angularly movable by the attendant through a lever *i* (Figure 5). On this spindle is formed or secured an arm *j* which at its outer end can bear on one side of a lateral peg *k* or other lateral projection on the slidable bar *a*, for enabling the attendant to move the bar to the position in which the supply of fuel by the pump is stopped. On the said spindle is also freely mounted an arm *m* which at its outer end is connected by a link *n* to a loading spring *o*. The other (and rounded end) is stepped to form two stop parts *p*, *q* with which can co-operate an adjustable abutment *r* connected to the slidable bar *a*.

For interconnecting the spindle *h* and the stop arm *m*, the spindle is formed with a longitudinal groove *s* in which lies a blade spring *t* (Figure 5), and in the bore of the arm is formed a groove *u* with which the spring blade can engage for securing the arm *m* to the spindle. Also in the arm is formed adjacent to the step between the stop parts *p*, *q*, a radial hole through which extends a pin *v*, the inner (and headed) end of which is supported on the blade spring and the outer end of which is operable by the abutment *r* on the arm connected to the slidable bar.

The lever *i* and arm *j* are loaded by a coiled spring *w* which at one end bears on the arm *j* and which at the other end is anchored to a stop *3* on the housing, the spring serving to hold the lever *i* and arm *j* in their rest position.

The mode of action of the mechanism is as follows:

To bring the engine to rest, the attendant operates the lever *i* above mentioned against the action of the spring *w* for moving the slidable bar *a* (through the medium of the arm *j*) to the limit position in which the bar *a* effects interruption of the supply of fuel by the pump as shown in Figure 3, the stop arm *m* being meanwhile held by the spring *o*. In this position the blade spring *t* is able to enter the groove *u* in the stop arm *m* which is thereby connected to the spindle *h*. Also in this position the stop part *p* which determines the normal maximum fuel supply lies in line with the abutment. After the engine has come to rest the attendant releases the lever *i*, and the spring *w* then returns the lever *i* and the arm *j* to their initial position thereby causing the stop arm *m* to take up the position shown

in Figure 4, which is limited by the engagement of a projection 2 on the arm *j* against the fixed stop 3. In this movement the stop arm *m* moves with the spindle *h* against the action of the spring *o*. The other part *q* of the stop then lies opposite the abutment *r* as shown in Figure 4, and allows the bar *a* to be moved to the position in which the pump can supply the required excess fuel. When the abutment *r* comes into contact with the pin *v* it depresses the latter and so disengages the blade spring *t* from the stop arm *m*, but movement of this arm by its loading spring *o* is prevented by contact of the abutment *r* with the shoulder between the parts *p*, *q* of the stop arm. When the engine is started on the next occasion the required excess fuel is thus automatically provided and as soon as the engine gains speed the pump governing mechanism moves the bar *a* (to the right) towards its reduced fuel position, thereby disengaging the abutment *r* from the shoulder on the stop arm and allowing the spring *o* connected to the stop arm to move this arm to the position in which the part *p* of the stop which determines the normal maximum supply is opposite the abutment *r* as shown in Figure 1. Thereafter the variation of pump output with varying load conditions proceeds in the usual manner. To stop the engine the driver returns the slideable bar to its limit position and in so doing the blade spring *t* re-engages the stop arm with the spindle in readiness for the next starting operation.

The above description applies equally to the alternative governing means shown in Figure 2.

By this invention the adaptation of the pump control mechanism to provide the required extra fuel when starting the engine is effected in a very simple and satisfactory manner. The invention is, however, not restricted to the example above described, as subordinate details may be modified to suit different requirements.

Having thus described my invention, what I claim as new and desire to secure by Letters Patent is:

1. For use with a liquid fuel injection pump of

the kind specified, means for enabling a quantity of fuel to be supplied to an engine in excess of the normal maximum when starting the engine, the said means comprising the combination with the governing means of the pump, of a spindle angularly operable by an attendant, an arm in fixed relation to the spindle and adapted to co-operate with the governing means, a second arm forming a two-part stop and freely mounted on the spindle, a spring device for interconnecting the stop arm with the spindle, a spring acting on the stop arm, and an abutment movable by the governing means and adapted to co-operate with the stop arm.

- 15 2. Means as and for the purpose claimed in claim 1, and comprising the combination of a longitudinally grooved spindle operable by an attendant, an arm in fixed relation to the spindle and adapted to co-operate with the governing means, an internally grooved stop arm freely mounted on the spindle and having a stepped and rounded end providing two stop parts, a spring blade located in the groove of the spindle and adapted to engage the groove in the stop arm, 20 a radially movable pin extending through the stop arm and adapted to disengage the spring blade from the stop arm, a spring acting on the stop arm, and an abutment movable by the governing means, the said abutment being adapted to act on the pin disengaging the spring blade and to co-operate with the stepped ends of the stop arm for determining the normal and excess maximum fuel supply.

WILFRID EDWARD WALTER NICOLLS.
